TATTING SHUTTLE

Edwin H. Larson, Chester, Conn., assignor to C. J. Bates & Son, Chester, Conn., a firm composed of Hamilton C. Bates, Wells C. Bates, and Hamilton C. Bates, Jr.

Application July 27, 1944, Serial No. 546,844

1 Claim. (Cl. 87—59)

This invention relates to improvements in tattling shuttles and the principal objects of the invention are directed to such shuttles having means to facilitate winding of thread or yarn on a spool component thereof.

Tattling shuttles of the prior art have consisted of side plates that have opposite ends in yielding contact and are secured intermediate their ends to a spool component. To wind thread or yarn around the spool component, the plates of the shuttle are held between the thumb and finger and the shuttle is rotated in such a manner that the thread passes between the ends of the side plates onto the spool.

According to one feature of the invention, a shuttle has side plates which intermediate their ends are associated with opposite ends of a spool component which is provided with a bore for frictionally receiving a rotating member or handle. The rotating member may be grasped between the fingers and rotated so as to rotate the bobbin whereby the yarn or thread is passed between the ends of the side plates and wound up on the spool, or the handle is held and the thread is passed around between the ends of the plates and around the spool.

According to another feature of the invention, the side plates have opposite ends secured together with a spool rotatable therebetween which has a bore in which is receivable a rotating member or handle adapted to rotate the spool for winding yarn or thread thereonto.

As a further feature of the invention the spool component is provided with a leading hole into the bore thereof so that the end of a yarn or thread passed therethrough may be secured in the bore by the rotating member or handle.

Various changes and modifications may be made in the practice of the invention without departing from the spirit and scope thereof.

In the drawing:

Fig. 1 is a side elevational view of a tattling shuttle embodying the novel features of the invention; and

Fig. 2 is a view similar to Fig. 1 showing a modified form of the invention.

Referring now to the drawing in detail, the invention will be more fully described.

Side plates 2 have inner faces secured to a spool component 4, as shown in Fig. 1. The said plates and spool may be made from various materials but there are numerous types of plastic which will produce a shuttle having the characteristics desired.

The spool portion 4 is provided with an axial

bore adapted to receive a rotating member such as 5. The said bore and the portion 6 of the member 5 according to one feature of the invention are preferably tapering for frictional engagement and a hole 8 is provided for receiving the inner end of a thread or yarn. The bore and portion 6 may be straight instead of tapering if desired.

With the end of a thread inserted in the hole 8 so as to lie within the bore of the spool the 10 rotating member when inserted in the bore pinches or clamps the thread end.

The rotating member may be engaged between the fingers or twirled thereby so as to rotate the bobbin so that the thread passes between the 15 ends of the side plates and is wound onto the spool.

According to the form of the invention shown in Fig. 2 side plates such as 10 have their opposite ends secured together.

20 A spool member 12 is provided which has flanges 14 secured to a hub portion 16 having opposite ends journaled in the plates 10 for rotation of the spool relative to the side plates.

The parts may be made from plastic material 25 and in any case the plates will preferably be yieldable so that they may be separated sufficiently to allow the spool to be removed from between them.

The part 16 is provided with a bore for frictionally receiving a part 18 of a handle or rotating member 17. A hole 20 in the part 16 permits the end of a thread to be inserted therein so as to lie in the bore and be clamped therein by the rotating member. Although not in all 35 cases necessary the bore of the spool and handle part fitting therein are preferably tapering.

The shuttle of Fig. 2 is held between the fingers with the rotating member inserted in the bore of the spool. The rotating member 17 is 40 rotated so as to rotate the spool for winding thread thereon, the end of the thread being clamped in the bore by the handle.

It may be desired to use a rotating member such as shown in Fig. 1 in connection with the construction shown in Fig. 2.

The invention may be embodied in other specific forms without departing from the essential characteristics thereof. Hence, the present embodiments are therefore to be considered in all 50 respects merely as being illustrative and not as being restrictive, the scope of the invention being indicated by the appended claim rather than by the foregoing description, and all modifications and variations as fall within the meaning and purview and range of equivalency of the ap-

pended claim are therefore intended to be embraced therein.

What it is desired to claim and secure by Letters Patent of the United States is:

A tatting shuttle comprising in combination, 5 a pair of similar elongated side plates having inner faces intermediate their ends secured to opposite ends of a central spool member to provide a unitary shuttle structure, said plates and central spool member provided with a central tapering bore and the spool member provided with a thread receiving hole leading into the

10 said bore transversely to the axis thereof, and a rotating member having a tapering end portion adapted for a wedging action in said bore, all adapted and arranged whereby a thread may be inserted through the thread receiving hole of the spool member into the bore thereof and the tapering end portion of the rotating member may be inserted in said bore for wedging said thread therein, and releasably securing said rotating member to the shuttle structure for rotation thereof.

EDWIN H. LARSON.
